[57] CLAIM

The ornamental design for an electronic game panel of soccer or the like, substantially as shown and described.

DESCRIPTION

FIG. 1 is a front elevation view of an electronic game panel of soccer or the like showing my new design; FIG. 2 is a front elevation view of another embodiment of the design;

FIG. 3 is a front elevation view of still another embodiment of the design;

FIG. 4 is a front elevation view of a further embodiment of the design;

FIG. 5 is a front elevation view of an even further embodiment of the design;

FIG. 6 is a rear elevation view of the electronic game panels of FIGS. 1-5;

FIG. 7 is a top elevation view of the electronic game panels of FIGS. 1-5;

FIG. 8 is a bottom elevation view of the electronic game panels of FIGS. 1-5;

FIG. 9 is a right hand elevation view of the electronic game panels of FIGS. 1-5;

FIG. 10 is a left hand elevation view of the electronic game panels of FIGS. 1-5;

The characteristic features of the invention are depicted in FIGS. 1-5;

The cross-hatched lines are used to depict various colors in the design according to the invention.
